UNITED STATES PATENT OFFICE.

CHARLES C. WIENTGE, OF PROVIDENCE, RHODE ISLAND, ASSIGNOR TO THE HOWARD STERLING COMPANY, OF SAME PLACE.

DESIGN FOR A METALLIC BORDER.

SPECIFICATION forming part of Design No. 23,145, dated March 20, 1894.

Application filed February 23, 1894. Serial No. 501,313. Term of patent 7 years.

To all whom it may concern:

Be it known that I, CHARLES C. WIENTGE, of Providence, in the county of Providence and State of Rhode Island, have invented and produced a new and original Design for Metallic Borders, of which the following is a specification, reference being had to the accompanying drawings, forming part thereof.

Figure 1 represents a view of a metallic border illustrating my new design. Fig. 2 represents an enlarged sectional view of the same taken on a line *a—b*, Fig. 1.

The leading features of my new design for borders consist in the irregular outline of the border together with the raised ornamentation consisting of a succession of ornaments of crown-like centers with foliated scrolls extending from the sides thereof and shell-like ornaments placed between the outer ends of the adjacent scrolls.

My design for borders consists in a succession of ornaments having crown-like centers the upper outline of which is divided into a central curve 6 and the side curves 7—7 joined to the central curve by the flattened curves 8—8, from the line of the central curve 6 extends a circular ornament 9. From the

curves 7—7 the upper outline curves gradually outward and downward as at 10—10 until the points 11—11 are reached, then follows 30 a succession of broken curves 12—12 until it meets the point 11—11 of the next ornament. The lower outline starting from the center of the crown-like ornament extends upwardly and outwardly in irregular lines to 13—13, then 35 curves upward to 14—14, then slightly downward and outward to meet the curves 14—14, then upward, and finally outward and upward to meet the lower curve 15 of the shell-like ornament 16. The surface ornamentation consists in the vertical convex portions or panels of the crown ornament, the band separating the crown portion from its apron 17, together with the foliated scrolls 18—18 and 19—19 curving toward the crown, and the 40 flutings 20—20 of the shell ornament. 45

What I claim is—

The design for a border as herein shown and described.

CHARLES C. WIENTGE.
